2 SHEETS—SHEET 2.

UNITED STATES PATENT OFFICE.

AUSTIN R. MARKEL, OF TYRONE, AND FRANK HAGGERTY, OF ALLEGHENY, PENNSYLVANIA

SMOKE-CONSUMER.

No. 862,265.

Specification of Letters Patent.

Patented Aug. 6, 1907.

Application filed December 29, 1906. Serial No. 350,085.

To all whom it may concern:

Be it known that we, AUSTIN R. MARKEL and FRANK HAGGERTY, citizens of the United States, residing at Tyrone and Allegheny, respectively, in the counties of Blair and Allegheny, respectively, and State of Pennsylvania, have invented certain new and useful Improvements in Smoke-Consumers, of which the following is a specification.

In manufacturing localities and particularly where 10 cheap fuel, such as soft coal is used in industrial pursuits, the question of disposing, or getting rid of the smoke, presents a serious problem. Many and various have been the attempts to solve the problem on an 15 economical and practicable basis but so far as has been ascertained, the difficulty has not been successfully overcome.

This invention has for its object to eliminate the free 20 carbon held in suspension in the products of combustion emanating from furnaces and other smoke producing devices and which free carbon is the source of evil in the smoke question.

In accordance with this invention, the free carbon with which the hot air and gases is laden is precipitated, steam being one of the essentials in the successful 25 operation, since it combines with the free carbon and causes the same to precipitate with the particles of condensation resulting from cooling of the steam in its travel through a passage, or conductor, in the length of 30 which condensers are located; as well as mixing devices for combining the steam and smoke.

An embodiment of the invention and a practical application thereof is shown in the accompanying drawings, in which:

Figure 1 is a side view of a passage, or conductor, 35 provided with adjunctive means for effecting the desired result. Fig. 2 is a top plan view of a portion of the conductor showing the parts on a larger scale. Fig. 3 is a vertical, central longitudinal section of the receiving portion of the conductor illustrating the 40 parts on a larger scale. Fig. 4 is a view similar to Fig. 3 of the delivery, or rear portion of the conductor. Fig. 5 is a vertical transverse section of a condenser on the line x—x of Fig. 3.

Corresponding and like parts are referred to in the 5 following description and indicated in all the views of the drawings by the same reference characters.

The conductor 1 may be of any construction, size and length and may be elevated, arranged at the surface, or located below the surface to any depth as found 10 best adapted to location and conditions.

A stack 2 is in communication with the delivery end of the conductor to discharge the hot air and gases at a convenient point after the smoke, or free carbon has been eliminated therefrom.

An air inlet 3 is provided at the receiving end of the

conductor and is usually closed but may be opened more or less to admit air in regulable quantity.

A steam pipe 4 likewise is in connection with the receiving end of the conductor and connects with the exhaust of engines, boilers, or other contrivances giving off spent steam, thereby preventing discharge of the steam into the atmosphere which is likewise objectionable since it hangs as a pall over the locality, obstructs sunlight and is otherwise injurious and objectionable.

The numeral 5 indicates the discharge from the smoke producer and in the case of a battery or gang of furnaces, each furnace has an independent connection with the conductor by means of a pipe-duct or conveyer 5.

It is to be understood in this connection that communication between the furnace, or smoke producer, and the conductor 1 may be had in any manner so long as the smoke and products of combustion are delivered to the conductor in which the separation takes place. 75 A deflector 6 is arranged within the conductor opposite to the discharge of each smoke conveyer 5 to prevent interference of one discharge with the other as also to give an initial upward direction to the smoke and products of combustion when entering the conductor. The 80 nozzle, or discharge of the steam pipe 4 is likewise deflected in the same direction as the deflectors 6 and has a like purpose.

Mixers 7 are located at intervals in the length of the conductor and each consists of a fan so arranged as to 85 physically combine the particles of steam with the particles of carbon contained in the smoke, gases and products of combustion.

The mixer, or fan 7, may be of any construction, in the event of the fan being mounted so as to rotate in 90 a plane corresponding with the length of the conductor as indicated most clearly in Figs. 3 and 4.

A wall, or baffle 8 is projected across the space of the conductor so as to cover one-half, preferably the lower half, of the fan, thereby causing the current 95 through the conductor to act upon the upper half of the fan only and effect rotation thereof with the current. The mixers, or fans 7, are automatically operated by the draft or current through the conductor and are not positively driven by direct connection 100 with any source of motive power.

A number of condensers are located in the length of the conductor, each condenser consisting of a chamber, or compartment 9 of suitable dimensions of larger capacity than the conductor. A wall 10 projects upward from the bottom of the chamber and terminates within a short distance from the top thereof.

The wall 10 constitutes a baffle and the current of moist smoke impacted thereagainst, is relieved in a great measure of the excessive humidity, the same be- 110

ing condensed, or precipitated, the particles of condensation carrying with them the free carbon which is precipitated in the bottom of the chamber.

Ingress is had into the condenser through a suitable door 11 and communication may be had from one part of the condenser to the other through an opening 12 provided in the wall, or partition 10.

To assist the separation of the free carbon, a jet of steam is injected into the condenser across the path of the current through the conductor. This jet is delivered through a nozzle, or pipe 13, which preferably inclines to the direction of the conductor so as to throw a jet across the current at an upward and forward angle. The jet of steam supplied through the nozzle, or pipe 13 may be derived from any source and is preferably waste, or spent steam, such as exhausted from an engine, or blown off from a boiler or other generator.

At, or near, the delivery end of the conductor, is located a fan 14, the purpose of which is to create a positive current through the conductor. This fan blower may be of any type commonly employed for creating an air blast. The fan blower 14 is positively driven from a suitable source of power, a drive belt 15 being shown as power translating means. The conductor is enlarged to form a compartment 16 in which the fan blower 14 is located. As illustrated, the fan blower is similar in construction and arrangement to the mixing fans 7 and in order that no back current may be created in the conductor a wall, or baffle 17, is arranged in the compartment 16 and covers the lower half of the fan, it being understood that the fan is rotated so that its upper portion travels towards the stack 2 so as to create a suction, or current, through the conductor from the receiving end 3 to the discharge 2.

In order that access may be readily had to the interior of the conductor, manholes 18 are provided at suitable points in the length thereof.

It is observed that the steam commingling with the smoke discharged into the conductor, renders said smoke moist or humid and the elimination of the excessive humidity by condensation results in separation and precipitation of the free carbon which constitutes the objectionable feature of smoke.

The precipitation and condensation takes place throughout the length of the conductor and more rapidly in the condensers, and the liquid precipitate commingling in the bottom of the conductor is directed to a common point of discharge by proper inclination of the bottom of the conductor.

As shown, a drain opening 19 is provided in the bottom of the last condenser and the bottom of the conductor slopes from opposite ends towards said opening, the walls, or partitions 8 and 10 having openings 20 in their lower ends so as not to obstruct the passage of the liquid precipitate in its travel towards the discharge, or drain opening 19.

The invention is equally applicable to steam boiler furnaces, either singly, or in battery, as well as to smelting or reverberatory furnaces, or in any adaptation to a smoke producing device employed in the industrial arts.

When the conductor is constructed under ground, it may be formed of masonry, but when at the surface,

or elevated above the ground, it may be advantageously formed of metal, or earthenware.

The jet of steam supplied to the condensers through the nozzles 13 may be in some instances advantageously derived from a boiler or generator, i. e., live steam. Obviously if the spent or waste steam has sufficient force, it may be discharged into the condensers through the nozzles 13. The steam combining with the smoke so as to eliminate the free particles of carbon therefrom may be supplied to the conductor at any point or points in the length thereof.

While the primary purpose of the fan 14 is to create a positive current through the conductor, it may also serve to augment the draft through the furnaces discharging into said conductor, thereby materially promoting the combustion of the fuel as well as intensifying the heat with the result that from a given quantity of fuel a greater number of units of heat are evolved and utilized.

Having thus described the invention, what is claimed as new is:

1. Means for separating and precipitating the free carbon of smoke, the same consisting of a conductor having an air inlet at one end and a discharge at the opposite end, means for discharging smoke into the air receiving end of the conductor, other means for discharging steam into the said conductor at a point between the air inlet and the smoke inlet, means for creating a current through said conductor from the air inlet to the discharge, a mixer arranged within the receiving end of the conductor near the smoke inlet to effect commingling or combining of the smoke and steam and means for separating the moistened free carbon from the fluid mixture in its passage through the conductor.

2. Means for separating and precipitating the free particles of carbon contained in the smoke, the same consisting of a conductor having an air inlet at one end and a discharge at the opposite end, means for discharging steam into the conductor adjacent or near the air inlet, other means for discharging smoke into the conductor in the rear of the steam discharge, means for creating a current through the conductor from the air inlet to the discharge, a mixer arranged in the conductor and automatically actuated by the current created in said conductor to effect commingling of the steam and smoke, and means for effecting separation of the moistened free carbon from the fluid mixture in its passage through the conductor.

3. Means for separating the particles of carbon from smoke, the same consisting of a conductor, having a stack, or discharge at one end and provided at, or near, the opposite end with an air inlet, means for discharging smoke and steam into the receiving end portion of the conductor, a mixer located in the conductor to effect a blending, or combining of the smoke and steam, means for creating a current through the conductor and a condenser arranged in the conductor for separating and precipitating the humid constituent of the combined fluid mixture.

4. In smoke eliminating means, the combination of a conductor provided with a discharge and with smoke and steam inlets, means for creating a current through the conductor, a mixer to effect blending of the smoke and steam in their passage through the conductor and a condenser in the length of the conductor, said condenser consisting of a chamber and a wall, or baffle, projected from the sides of the condenser across the path of the mixture of smoke and steam to deflect the same and facilitate separation and precipitation of the free carbon held in said mixture, said wall being spaced at one of its edges from a side of the condenser to provide an outlet for the aforesaid fluid mixture.

5. Means for eliminating the particles of carbon from smoke, the same consisting of a conductor, having a discharge at one end and provided at, or near, the opposite end with steam and smoke inlets, means for creating a current through the conductor, mixers arranged in the

length of the conductor, to effect commingling or blending of the smoke and steam, and condensers in the length of the conductor alternating with the mixers to effect separation and precipitation of the humid portion of the fluid mixture passing through the conductor.

5 6. In combination, a conductor provided at one end with a regulable air inlet, and at the opposite end with a discharge, a suction fan located near the discharge end of the conductor for creating a current therethrough, mixing fans arranged at intervals in the length of the conductor and automatically actuated by the current therethrough to effect blending of the steam and smoke, the condensers in the length of the conductor alternating

with the mixing fans, and steam and smoke inlets at, or near, the receiving end of the conductor.
